HANDLE ATTACHMENT FOR PAPER BOXES

David H. Shapiro, Montreal, Quebec, Canada

Application April 17, 1937, Serial No. 137,458
In Canada January 12, 1937

16 Claims. (Cl. 229—52)

This invention relates to handle attachments for paper boxes and comprises a metal handle member designed for convenient application to paper boxes of the type comprising half-sections adapted to fit one within the other so that, in the closed condition of the box, the top wall of the outer section is superposed on the top wall of the inner section. More particularly, the handle member provided in accordance with the present invention is designed so that it may be readily slipped onto the top wall of the inner section of the box and then passed through a slot in the top wall of the outer section to thereby secure the two sections together in addition to providing a carrying handle.

In its preferred embodiment the improved handle member comprises a wire bail having its side arms bent to form spring clips adapted to slide on and grip the top wall of the inner section of the box, the bail portion of the handle member being thus disposed so that it may be conveniently passed through the slotted top wall of the outer section of the box as the two sections are closed together.

According to another embodiment of this invention a wooden handgrip is removably carried between two metal side arms formed as integral extensions of a wire clip portion which is slipped onto the top wall of the inner section of the box. In this case the metal side arms of the bail portion are passed through the top wall of the outer section of the box prior to the application of the wooden handgrip.

According to a further embodiment of the invention the improved handle member is combined with a hanger the whole preferably forming a unitary, integral structure.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated in the annexed drawings, wherein like parts are designated by the same reference characters throughout the several views.

In the drawings:

Figure 1 is a perspective view of the preferred type of handle member provided in accordance with this invention.

Figure 2 is a perspective view of a well known type of paper box (two-piece) showing the manner in which the handle member appearing in

Fig. 1 is applied to the top wall of the inner section piece of the box.

Figure 3 is a perspective view showing the paper box in closed condition with the bail portion of the handle member passing through the slot in the top wall of the outer section of the box.

Figure 4 is a fragmentary transverse sectional view taken along the line 4—4 of Fig. 3.

Figure 5 is a view of a slight modification with respect to the application of the handle member shown in Fig. 1.

Figure 6 is a perspective view of a modified type of handle member.

Figure 7 is a perspective view of a one-piece paper box showing the manner in which the handle member appearing in Fig. 6 is engaged with the top wall of the inner section of the box.

Figure 8 is a perspective view showing the manner in which the two half-sections of the box are secured together by portions of the handle member appearing in Figs. 5 and 6.

Figure 9 is a view similar to Fig. 8, but showing the handle member completed by the application of the wooden handgrip.

Figure 10 is a fragmentary transverse sectional view along the line 10—10 of Fig. 9.

Figure 11 is a perspective view of one half of a box showing the invention embodying a combined handle and hanger.

Figure 12 is a perspective detail of the combined handle and hanger shown in Fig. 11.

The advantages of the invention as here outlined are best realized when all of its features and instrumentalities of each embodiment are combined in one and the same structure, but, useful devices may be produced embodying less than the whole.

It will be obvious to those skilled in the art to which the invention appertains, that the same may be incorporated in several different constructions. The accompanying drawings, therefore, is submitted merely as showing the preferred exemplifications of the invention.

The handle member shown in Figure 1 comprises a wire bail presenting a handle bar 5 and side arms 6, the latter being reversely bent at their lower ends to provide U-shaped spring clips generally indicated at 7. In applying this type of handle member the clips 7 are first slid onto the top wall 8 of the inner section 9 of the box shown in Fig. 2. The clips 7 are preferably designed so that, when the handle member is applied as shown in Figure 2, the handle bar 5 and the arms 6 will be located approximately midway between the longitudinal sides of the wall 8. 55

The two sections of the box are then closed together so that the inner section 9 is disposed within the outer section 10 as shown in Figure 3. During this operation the bail portion of the handle member is passed through a slot 11 formed in the top wall 12 of the outer section 10. An adhesive strip S may be applied to prevent the sections 9, 10 from separating at the bottom of the box when the latter is being carried by the handle.

In applying the handle member to larger sizes of boxes the top wall 8 of the inner section 9 may be provided with notches 13 (Fig. 5) in which the bight portion 1a of the clips 7 are fitted, to center the bail portion of the handle between the longitudinal edges of the wall B so that it may be conveniently passed through the centrally located slot in the top wall of the outer section.

20 In the modification shown in Figure 6 the bail portion of the handle member comprises a wooden handgrip 15 removably carried between the upper ends of a pair of side arms 16. In this case the arms 16 are formed as integral vertical extensions of the upper members 11a of a pair of spring clips generally indicated at 17. The lower members 17b of the spring clips 17 are made longer than the top members 11a and are joined together by a cross-bar 18.

30 Figure 7 shows by way of illustration, a one-piece box to which the modification shown in Figure 6 is applied.

In applying this type of handle member (Figure 6) the clips 17 are first engaged with the top wall of the inner section 9' of the box as shown in Figure 7. The two sections 9', 10' of the box are then closed together as shown in Figure 8 and, in the course of this operation, the arms 16 are passed upwardly through openings 40 19 provided in the top wall 12 of the outer section of the box. The wooden handgrip 15 is then fitted in place between the upper ends of the arms 16 as shown in Figure 9. In this connection it will be noted that the upper ends of the arms 16 terminate in inwardly directed pintles 16a which are fitted in sockets 15a provided in the ends of the handgrip 15.

45 In the modification shown in Figure 12, the handle member comprises a wire bail presenting a handle bar 20 and side arms 21, the latter being reversely bent at their lower ends to provide U-shaped spring clips indicated at 22. At the lower end 23 of these U-shaped clips the wire bail is bent to form extensions 24 and outwardly extending arms 25 from which is further extended the wire bail to form the bar 26 constituting the development of the hanger A. Figure 11 shows this type of combined handle and hanger applied to inner section 9 of the box depicted generally 50 in Fig. 2.

Having thus described my invention, what I claim is:

1. In combination, a box comprising half portions fitted one within the other so that the top 55 wall of the outer section is superposed on the top wall of the inner section and a handle member comprising a clip portion removably fitted on the top wall of the inner section of the box and a bail portion extending outwardly through the top wall 70 of the outer section of the box.

2. The combination set forth in claim 1 in which the bail portion of the handle comprises a U-shaped member formed as an integral part of the clip portion.

75 3. The combination set forth in claim 1 in

which the bail portion of the handle member comprises a pair of side arms formed as integral continuations of the clip portion and a wooden handgrip removably carried between said arms.

4. A metal handle attachment for paper boxes of the character described comprising a bail having its side arms bent to form a single pair of spring clips, said clips being arranged in planes each extending at an angle to the plane of the bail.

10 5. A metal handle attachment for paper boxes of the character described comprising a wire bail having its side arms reversely bent at their lower extremities to provide a single pair of substantially U-shaped spring clips, said clips being arranged in planes each extending at an angle to the plane of the bail.

15 6. A metal handle member for boxes of the character described comprising a wire bent to form a pair of substantially U-shaped spring 20 clips having their lower members joined together by a cross-bar, an arm projecting upwardly from the upper member of each clip and a handgrip removably fitted between the upper ends of said arms.

25 7. In combination, a box comprising half portions fitted one within the other so that the top wall of the outer section is superposed on the top wall of the inner section and a combination handle and hanger comprising a clip portion removably fitted on the top wall of the inner section of the box, a garment hanger depending from said clip portion, and a bail portion extending outwardly through the top wall of the outer section of the box.

30 8. The combination set forth in claim 7 in which the bail portion of the handle and the hanger are formed as integral parts of the clip portion.

35 9. A combination metal handle and hanger attachment for boxes of the character described comprising a wire bail having its side arms bent to form spring clips, the latter being extended to form a garment hanger.

40 10. A metal handle attachment for paper boxes of the character described comprising a wire bail having its side arms reversely bent at their lower extremities to provide substantially U-shaped spring clips, and extended from said clips to provide a garment hanger.

45 11. A carrying handle for boxes comprising a bail portion and a single U-shaped portion at each opposite end of the bail portion and arranged substantially parallel with each other and in planes at an angle to the plane of the bail portion, said U-shaped portions being adapted for embracing one wall of a box through their open ends.

50 12. In combination, a box having inner and outer portions one superimposed upon the other, the outer portion having an opening, and a handle having a single pair of clamping means embracing the inner portion of the box for retaining said handle thereon, with a bail attached to said clamping means and extending outwardly therefrom through said opening.

55 13. In combination, a box having inner and outer portions one superimposed upon the other, the outer portion having an opening, and a holder including a handle having a single pair of resilient means for yieldingly engaging the inner portion of the box, with the handle projecting through said opening, said handle having a garment hanger portion connected therewith and extending within the box.

14. A metal handle attachment for paper boxes comprising a wire bail having its side arms bent to form spring clips, said clips being arranged in a plane at an angle to that of the bail.
- 5 15. A metal handle attachment for a box in which the box has sections fitted one within the other so that the top wall of the outer section is superimposable on the top wall of the inner section and the top wall of the outer section 10 has an opening therethrough, said handle comprising a bail having side arms bent to form clips for removably fitting on the top wall of the inner section of the box, said bail being adapted to extend through the opening in the 15 outer section of the box serving to keep the sections of the box together and as a handle for carrying the box.
16. A carrying handle for boxes comprising arms, a U-shaped portion attached to each arm with said arm projecting upwardly therefrom, 5 said U-shaped portions being arranged approximately parallel with each other and in planes at an angle to the plane of the arms, means joining said U-shaped portions together and holding the same in spaced relation, and a hand- 10 grip removably fitted between the upper ends of said arms, said U-shaped portions being adapted for receiving an edge of a box through their open ends.

DAVID H. SHAPIRO. 15
